A. Z. SEROR & E. J. HOYER.

FAN.

APPLICATION FILED MAY 17, 1915.

1,243,637.

Patented Oct. 16, 1917.

UNITED STATES PATENT OFFICE.

ALBERT Z. SEROR AND EDWARD J. HOYER, OF CHICAGO, ILLINOIS.

FAN.

1,243,637.

Specification of Letters Patent. Patented Oct. 16, 1917.

Application filed May 17, 1915. Serial No. 28,636.

To all whom it may concern:

Be it known that we, ALBERT Z. SEROR and EDWARD J. HOYER, citizens of the United States, and residents of Chicago, in the county of Cook and State of Illinois, have invented certain new and useful Improvements in Fans, of which the following is a specification.

This invention relates to fans.

10 The object of the invention is to provide a gear-driven, hand-operated rotary fan which may be conveniently carried in a vest pocket. To this end a fan of our invention comprises the various features, combinations of features and details of construction hereinafter described and claimed.

In the accompanying drawing, in which our invention is fully illustrated,

20 Figure 1 is a front view of our improved fan with the vanes or blades extended.

Fig. 2 is a similar view thereof with the vanes or blades folded.

Fig. 3 is an enlarged side of our improved fan with the casing removed.

25 Fig. 4 is an enlarged sectional view on the line 4—4 of Fig. 3, showing the gearing; and

30 Figs. 5, 6 and 7 are, respectively, enlarged detail sectional views of the fan proper on the lines 5—5 and 6—6 of Fig. 1 and 7—7 of Fig. 5.

Referring now to the drawing, 1 designates the fan proper, 2 the fan shaft to which the fan 1 is secured, and 3 is a box 35 or casing within which the gearing for driving said fan is inclosed, and which affords means for holding and operating the fan without interfering with the operative parts thereof.

40 As regards its usual features and, excepting as hereinafter particularly pointed out, the fan proper 1 is of a usual type and will be readily understood from the drawing without a detailed description thereof.

45 To provide for folding the blades or vanes of said fan into the position shown in Fig. 1, said blades or vanes are mounted on a bushing 4 so as to turn thereon relative to each other, and to provide for securing said vanes or blades in folded and extended positions, said vanes or blades are provided at their attached ends, one with a bead 5 and the other with a groove 6, which, as shown, extend radially on both 50 sides of the centers of said vanes or blades and in such relation that said bead 5 will

engage the groove or slot 6 both when said vanes are folded and when they are unfolded. A spring 7 inserted between a flange of the bushing 4 and the outer side of 60 one of the fan blades or vanes will maintain said bead and groove yieldingly in engagement with each other and will also operate to frictionally secure said fan blades or vanes to said bushing to cause them to 65 turn with said bushing. As shown, said spring 7 consists of a three clip spring provided with a central opening adapted to receive the bushing 4.

The fan shaft 2 is mounted to rotate 70 freely in a suitable frame and is adapted to be driven by suitable gearing likewise mounted in said frame. As shown, said frame consists of spaced plates 8 and 9, which are connected at their ends by cross 75 pieces 10.

The gearing for driving the fan shaft 2 consists of a plunger 11, which is supported by suitable guides on the gearing frame so as to be freely movable endwise. As 80 shown, the guides for said plunger consist of a bearing in one of the cross frame pieces 10 to which said plunger is fitted, and a stud 12 secured in the side frame plate 8 which engages a slot 13 formed lengthwise in said 85 plunger.

Formed in one side of said plunger are rack teeth 14 which are connected in train with a pinion 15 secured to the fan shaft. As shown, said train of gears comprises a 90 pinion 16 secured to a shaft 17 mounted to rotate freely in bearings in the side frame plates 8 and 9 and a relatively much larger pinion 18 mounted to rotate freely on said shaft 17 and which intermeshes with 95 the pinion 15 on the fan shaft. Rotation is imparted to the pinion 18 from the pinion 16 by means of a ratchet wheel 19 secured to the shaft 17 so as to rotate with the pinion 16, the teeth of which are adapted to be engaged by a spring pawl 20 pivoted to the pinion 18.

The plunger 11 projects through the end of the box or casing 3 and is maintained yieldingly in extended position by means 105 of a spring 21 applied thereto, the relation being such that depressing said plunger 11 will impart rotation to the fan shaft 2 at a relatively high speed, the spring 21 operating to again return said plunger to its 110 extended position.

The box or casing 3 is made as small as

possible to contain the gearing and gearing frame without binding, and is provided with holes or openings for the fan shaft 2 and the plunger 11.

5 In actual practice we contemplate making the gearing frame and gearing of such size that it can be contained in a box or casing 2 inches long, by $1\frac{1}{2}$ inches wide and $\frac{1}{16}$ of an inch thick, and the fan, when folded being 2 inches long. Also, our improved fan has no separate handle, but is designed to be held and operated by a thumb and finger of one hand, one applied to the end of the plunger 11 and the other to the side 10 or end of the casing 3 opposite to that from which said plunger projects. Thus, when folded, said fan may very conveniently be carried in a vest pocket.

The bushing 4 is adapted to be secured 20 to the projecting end of the fan shaft 2 so as to rotate therewith, being preferably provided with an axial hole or bore adapted to frictionally engage said shaft.

It will be observed that a further feature 25 of importance lies in having the operating plunger extend out through the casing at one end thereof, so that the device may be firmly held in one hand (with the thumb on the end of the plunger and one or more 30 fingers against the opposite end of the casing) and conveniently and easily operated. It will be observed also that when the finger or fingers tire, other fingers may be brought into use, so that the device may be operated 35 continuously without annoyance from appreciable fatigue on the part of the operator. This construction has also the important advantage that the casing may be reduced to a comparatively small size, preferably 40 small enough to fall within the area of the field of rotation of the fan, this smallness of the casing being permitted by reason of the fact that the construction permits the thumb to be reciprocated in operating the 45 plunger back of the fan blades. Thus permitting the fingers to grasp the casing and the plunger back of the fan blades is further facilitated by locating the plunger near the back wall of the casing, that is, a sufficient 50 distance back of the fan blades to obtain a firm grasp on the end of the plunger with the thumb without having the fan blades in their rotation strike the thumb.

We claim:

55 1. In a fan, the combination of a fan shaft, a pinion thereon, a reciprocating plunger, a rack on said plunger, a spring applied to said plunger for maintaining the same normally extended, gearing in train 60 with the rack on said plunger and the pinion on said fan shaft, a casing which encloses said gearing provided with holes through which said plunger and fan shaft project, a fan secured to rotate with said 65 fan shaft the blades of which are pivotally

movable relatively to each other to provide for folding and extending said fan blades, means for maintaining said fan blades yieldingly in folded and extended positions.

2. A runner for a rotary fan the blades 70 of which are pivotally movable relatively to each other to provide for folding and extending said fan blades, and means for locking said fan blades yieldingly in folded and extended positions, substantially as described. 75

3. A runner for a rotary fan, the blades of which are pivotally movable relatively to each other to provide for folding and extending said blades, and means for locking so said blades yieldingly in folded as well as extended positions, said means consisting of a corresponding interfitting bead and groove formed on adjacent faces of the fan blades, and a spring yieldingly pressing the 85 fan blades into contact with each other.

4. A runner for a rotary fan, the blades of which are pivotally movable relatively to each other to provide for folding and extending said blades, and means for locking 90 so said blades yieldingly in folded and extended positions, said means consisting of an interfitting bead and groove arranged radially with respect to the axis of rotation of the fan and extending on opposite sides 95 of said axis, and spring means for yieldingly pressing the fan blades together.

5. In a pocket fan, the combination of a casing, a fan shaft mounted therein and extending through the front wall thereof, fan blades mounted on the projecting end of said shaft, a pinion on said shaft within the casing, an operating plunger extending through one end of the casing and reciprocable toward and from the fan shaft, 100 means in the casing for normally maintaining the plunger yieldingly extended, a rack carried by the inner end of said plunger, and gearing in train with the rack and the pinion on the fan shaft for imparting continuous rotary motion to the fan shaft upon reciprocation of the plunger, whereby said fan is adapted to be supported and operated by a thumb and finger of one hand. 105

6. In a pocket fan, the combination of a 110 casing, a fan shaft extending through the front wall thereof, fan blades mounted on said shaft and capable of relative pivotal movement thereon to provide for nesting the blades when not in use, an operating 115 plunger extending through one end of the casing and reciprocable toward and from the opposite end of the casing, and means in the casing for normally pressing the plunger outwardly and for imparting a continuous rotary motion to the fan shaft upon reciprocation of the plunger.

7. In a pocket fan, the combination of a 120 casing, a fan shaft extending through the front wall near one end of the casing, fan 125

blades mounted on said shaft capable of relative pivotal movement thereon to provide for nesting the blades when not in use, an operating plunger extending through the 5 end of the casing opposite that at which the fan shaft is mounted, said plunger being located close to the rear wall of the casing and reciprocable toward and from the fan shaft, and means in the casing for normally 10 pressing the plunger outwardly and for imparting a continuous rotary motion to the fan shaft, when the plunger is reciprocated, the nested blades being substantially the

same length as the casing and plunger, and the casing and plunger being of such size 15 as to be adapted to be held and operated by a thumb and finger of one hand.

In testimony that we claim the foregoing as our invention we affix our signatures, in the presence of two subscribing witnesses, 20 this 15th day of May, 1915.
